INVENTOR.

Charles H. Fallows
BY
Horatio E. Bellows
ATTORNEY

UNITED STATES PATENT OFFICE.

CHARLES H. FALLOWS, OF PROVIDENCE, RHODE ISLAND.

KEY HOLDER.

Application filed December 9, 1925. Serial No. 74,358.

To all whom it may concern:

Be it known that I, CHARLES H. FALLOWS, a citizen of the United States, residing at Providence, in the county of Providence and State of Rhode Island, have invented 5 certain new and useful Improvements in Key Holders, of which the following is a specification.

My invention relates to holders for keys 10 adapted for use in case or backing of flexible material adapted for pocket use.

The essential objects of my invention are to afford universal action of the snap hooks or movement of the latter in any desired 15 direction; to secure such action with a minimum of friction; to insure that the action of each hook be wholly independent and distinct from the action of any other hook or supporting part; and to attain these ends in 20 a strong and inexpensive structure.

To the above ends essentially my invention consists in such parts and in such combinations of parts as fall within the scope of the appended claim.

25 In the accompanying drawings which form a part of this specification

Figure 1 is a front elevation of my holder embodied in a key case,

Figure 2, an end elevation of the holder, 30 Figure 3, a partial fragmentary section on line 3—3 of Figure 2, and

Figure 4, a detail view of one of the suspension units.

Like reference characters indicate like 35 parts throughout the views.

In the drawings 4 is an enclosing case of flexible material comprising a body portion 5, flaps 6, and the usual fastening members 7. It is in conjunction with the above 40 or other suitable case of this type that my holder is intended to be applied.

The holder includes a base or attaching plate 10 of pliable or resilient metal, preferably of square or oblong shape, and provided 45 with holes 11 adapted to receive rivets or eyelets 12 for attachment to the case.

Integral with the upper edge of the plate 10 are a series of loops 15, each loop be-

ing interspaced as at 16. Suspension members are provided, each consisting of a block 50 18 with trunnions 19 and provided with a centrally disposed vertical hole or bore 20. Each suspension block is located in one of the spaces 16 with its sides in slidable contact with the ends of adjacent loops 15, while 55 its trunnions 19 have circular movement in the latter. The trunnions of one block are rotatable independently of the movement of the trunnions of the next adjacent block from which they are spaced. 60

Snap hooks are employed comprising shanks 23 and loops 24. The upper ends of the shanks are reduced to form necks 26 which swivel in the holes 20 and terminate in heads 28 resting loosely on the upper 65 faces of the blocks.

The snap hooks are for the reception of the keys which are engaged therewith in the usual manner.

It will be observed that the hooks both 70 swing and swivel so that universal action is secured, and it will be further observed that each block is distinct from each other block. This is important not only in preventing movement of an adjacent block, but 75 also because it permits independent repair and substitution of any particular block by opening up a single loop 15. The block and trunnion construction it will be noted permits their formation by suitable dies from 80 blank strips of metal which renders the expense of manufacture insignificant.

I claim:—

In an article of the character described, 85 an attaching plate, a plurality of longitudinally disposed loops integral with the plate and interspaced from each other, blocks loosely fitting in the spaces between the loops and provided with holes, trunnions on the blocks journaled in the loops, snap hooks, 90 necks on the hooks extending loosely through the holes, and heads upon the necks, resting upon the blocks.

In testimony whereof I have affixed my signature.

CHARLES H. FALLOWS.
